UNITED STATES PATENT OFFICE.

WILLIAM A. HOUCK, OF READING, PENNSYLVANIA.

DESIGN FOR A COP-MOUNTING BRACKET FOR KNITTING-MACHINES.

57,435.

Specification for Design.

Patented Mar. 29, 1921.

Application filed November 7, 1919. Serial No. 336,481. Term of patent 7 years.

To all whom it may concern:

Be it known that I, WILLIAM A. HOUCK, a citizen of the United States, residing at Reading, in the county of Berks and State of Pennsylvania, have invented a certain new, original, and ornamental Design for a Cop-Mounting Bracket for Knitting-Machines, of which the following is a specification, reference being had to the accompanying drawing, forming part thereof.

Figure 1 is a side elevation, and Fig. 2 an edge view of a cop mounting bracket for knitting machines, showing my new design.

I claim,—

The ornamental design for a cop mounting bracket for knitting machines, as shown.

In testimony whereof I affix my signature.

WILLIAM A. HOUCK.
